CLAIM

The ornamental design for a support structure for dentistry applications, as shown and described.

DESCRIPTION

FIG. 1 is a front perspective view of a support structure for dentistry applications, said drawing showing a lamp and a control module therefore attached to a support structure for dentistry applications embodying my new design;

FIG. 2 is a rear perspective view thereof; and,

FIG. 3 is a top view thereof.

1 Claim, 3 Drawing Sheets

FIG. 2

FIG. 3
